D 19839

UNITED STATES PATENT OFFICE.

VAN ZANDT M. MOORE, OF MILWAUKEE, WISCONSIN.

DESIGN FOR A REGISTER.

SPECIFICATION forming part of Design No. 19,839, dated May 13, 1890.

Application filed April 7, 1890. Serial No. 346,997. Term of patent 14 years.

To all whom it may concern:

Be it known that I, VAN ZANDT M. MOORE, a citizen of the United States, residing at Milwaukee, in the county of Milwaukee and State of Wisconsin, have invented and produced a new and original Design for Registers; and I do declare the following to be a full, clear, and exact description of the same, reference being had to the accompanying photograph, forming a part thereof.

The said photograph is a plan of a register showing my design.

The leading features of my design consist in a plain rectangular open surface *a*, within which, at the corners thereof, are open pear-shaped figures *b b* and a series of straight lines *c c*, four in number, extending between the said pear-shaped figures *b b*, and united to the outer rectangular surface *a* by figures *d*, straight at their ends and having solid circular centers, and by other figures *e*, straight at their inner ends and having open circles at their outer ends, the whole forming the inner border of my design. Within this border, at the center of each end and side, are other open pear-shaped figures *f f*, connected

by four straight lines *g g g g*, arranged in the form of a lozenge, and having interior obliquely-angular lines *h h*, curved and angular cross-lines *i i*, and an open circular central figure *j*, while outside of said lozenge-shaped figure are series of inclined straight lines *k k*, open circles *m m*, and antler-shaped curved lines *n n*, substantially as shown.

What I claim is—

The design for registers, consisting of an open rectangular surface, with pear-shaped figures at the inner corners thereof, an inner connected border, and a central lozenge-shaped figure having curved and angular cross-lines and inner obliquely-angular lines, and a central open circular figure connected with said border by pear-shaped and circular figures, inclined straight lines, and antler-shaped curved lines, substantially as shown in the accompanying photograph.

In testimony whereof I affix my signature in presence of two witnesses.

VAN ZANDT M. MOORE.

Witnesses:

N. E. OLIPHANT,
WM. KLUG.
